EXCREMENT DISPOSAL DEVICE

Lucille Inez Taylor, Lincoln, Nebr.

Application March 17, 1952, Serial No. 276,979

1. Claim. (Cl. 4-1)

1 This invention relates to excrement disposal devices for colostomy patients after a colostomy, and in particular a receptacle and a stand for supporting the receptacle in such a position that a patient may take care of his requirements without the assistance of an attendant or nurse.

The purpose of this invention is to eliminate the necessity of an attendant handling the excrement of a patient after a colostomy.

After an operation for removing a colostomy or making an incision in the colon it is undesirable for excrement to pass through the colon tube and an incision is made in the side of the patient for this purpose. Because the incision is made in the front of the patient the use of a conventional bedpan is difficult and because of the odor handling of the excrement is objectionable. With this thought in mind this invention contemplates a receptacle adapted to be positioned between the legs of a patient with an inlet nipple extended from one side and positioned to fit snugly over an incision of a colostomy and having a discharge tube extended from the lower end, a stand for supporting the receptacle, and a colon irrigating tube also carried by the stand.

The object of this invention is, therefore, to provide means for forming and supporting a receptacle whereby colostomy patients may dispose of excrement without the assistance of an attendant.

Another object of the invention is to provide means whereby excrement of colostomy patients may be deposited directly through a receptacle into a toilet bowl.

Another object of the invention is to provide means for supporting a receptacle for receiving excrement of a patient after an operation for a colostomy in which the receptacle may be adjusted vertically and horizontally to register with the opening in the side of the patient.

A further object of the invention is to provide a device to facilitate patients after a colostomy disposing of excrement in which means is also provided for irrigating the colon.

A still further object of the invention is to provide an excrement disposing and colon irrigating device particularly adapted for patients after a colostomy in which the device is of a simple and economical construction.

With these and other objects and advantages in view the invention embodies a receptacle having a substantially cylindrical body with leg receiving recesses in the sides of the lower end, a nipple having a resilient body engaging collar on the extended end positioned on the side of

2 the receptacle facing the body of a patient, a discharge tube positioned to extend between the legs of a patient, a transparent cover on the receptacle, and a stand having a bracket for supporting the receptacle on one side and colon irrigating apparatus on the upper end.

Other features and advantages of the invention will appear from the following description taken in connection with the drawing, wherein:

10 Figure 1 is a side elevational view of the improved excrement disposal device illustrating the device with a receiving nipple of the device positioned against a patient and showing a discharge tube of the device extended into a toilet bowl, the patient and toilet bowl being shown in dotted lines.

Figure 2 is a plan view of the receptacle of the device, with the parts shown on an enlarged scale.

20 Figure 3 is a vertical section through the receptacle of the device, said section being taken on line 3-3 of Figure 2.

Figure 4 is a front elevational view showing the receptacle of the excrement disposal device, 25 also with the parts shown on an enlarged scale.

Referring now to the drawing wherein like reference characters denote corresponding parts the excrement disposal device of this invention includes a receptacle 10 having an inlet nipple 12 in the front, a discharge tube 14 extended from the lower end, an opening 16 in one side and a transparent cover 18, a stand having a post 20 supported with three legs 22 and having a tray 24 on the upper end, and a bracket 26 having a ring 28 in which the receptacle 10 is positioned and a collar 30 slidably mounted on the post and secured in adjusted positions with a set screw 32.

40 The receptacle 10 is formed with a substantially cylindrical body having leg receiving recesses 34 and 36 in the sides of the lower end and a bell-like rim 38 around the upper end and upon which the cover 18 is positioned. The cover is provided with a flange 40 that extends over the rim 38 and frictionally retains the cover in position upon the receptacle.

45 The inlet nipple 12 which extends from the front of the body of the receptacle is positioned at one side of the center, as shown in Figure 4, and the extended end of the nipple is provided with an annular collar 42, which is formed of resilient material. The collar is provided with an annular recess 44 into which the end of the nipple extends, as shown in Figure 3.

50 The collar 42 is comparatively soft whereby

3

with the collar contacting the skin of a patient with the nipple placed over an opening in the side of the patient, the opening is substantially sealed and all excrement passing through the opening passes into the receptacle, and from the receptacle through the discharge tube 14 into a toilet bowl, as indicated by the dotted lines 46, and upon which the patient, as indicated by the dotted lines 48, is positioned.

The opening 16 in the side of the receptacle provides a vent and also facilitates cleaning the interior of the receptacle.

The three legs 22 supporting the post 20 of the stand are positioned whereby with one leg extended away from the bowl the two other legs straddle the bowl, as shown in Figure 1. The legs 22 are provided with rollers 50 to facilitate moving the device from one position to another.

The tray 24 mounted on the upper end of the post is provided with an annular flange 52 and the tray, which supports a container 54, is provided with an opening 56 through which a colon irrigating tube, as indicated by the numeral 58, extends. The tube 58 extends from the container 54 and when not in use the extended end thereof is temporarily held in a clip 60 which extends from the container.

With this apparatus a patient, after a colostomy, and positioned on a toilet bowl, as shown in dotted lines in Figure 1, may irrigate the colon and dispose of excrement by drawing the device to the position shown in Figure 1, with the rubber collar of the nipple 12 positioned over the outlet opening in his side, and the excrement will pass directly into the bowl. The position of the receptacle is readily adjustable on the stand so that the nipple may be positioned to cover the opening of the patient.

From the foregoing description it is thought to be obvious that an excrement disposal device constructed in accordance with my invention is

5

10

15

20

25

particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

What is claimed is:

In an excrement disposal device, the combination which comprises a cylindrical receptacle having leg receiving recesses in the sides of the lower end thereof, with a discharge tube extended from the lower end, an inlet nipple extended from the front, and having a bell-like flange around the upper end, a transparent cover positioned on the flange at the upper end of the receptacle, a resilient collar positioned on the extended end of said nipple, a post supported by radially disposed legs and having a tray on the upper end, a bracket having a ring on an extended end thereof adjustably mounted on said post, said ring of the bracket receiving the receptacle with the bell-like flange resting upon the ring, a container positioned on the tray at the upper end of the post, and a colon irrigating tube extended from said container.

LUCILLE INEZ TAYLOR.
